(57) **CLAIM**

I claim the ornamental design for a vertical smoker, as shown and described.

DESCRIPTION

FIG. 1 is a perspective view of a vertical smoker showing my new design;

FIG. 2 is a front elevational view thereof;

FIG. 3 is a left side elevational view thereof, the right side elevational view being a mirror image thereof;

FIG. 4 is a rear elevational view thereof;

FIG. 5 is a top plan view thereof; and,

FIG. 6 is a bottom plan view thereof.

The wheels shown in dotted lines are for illustrative purposes only and form no part of the claimed design.
